UNITED STATES PATENT OFFICE.

CHARLES M. DAYTON, OF BOWLING GREEN, KENTUCKY.

DESIGN FOR A BADGE.

SPECIFICATION forming part of Design No. 32,983, dated July 24, 1900.

Application filed June 25, 1900. Serial No. 21,575. Term of patent 31 years.

To all whom it may concern:

Be it known that I, CHARLES M. DAYTON, a citizen of the United States, residing at Bowling Green, in the county of Warren and state of Kentucky, have invented and produced a new and original Design for a Badge, of which the following is a specification.

This invention relates to a design for a badge; and the essential feature resides in a pictorial representation of the rising sun in the background, two male figures in the foreground clasping hands, working implements in part supported by one of the figures, and two objects between and in rear of the figures.

15 The accompanying drawing discloses the features of the design, and the numeral 1 designates the rising sun showing behind hills 2 in the background, a field 3 being between the hills and the foreground. In the foreground are two male figures 4 and 5 in erect position, facing each other, with right hands clasped, the figure 4 having the left hand to the rear and resting on the end of the handle of a pick 6. Between the two figures a hammer 7 is shown lying on the ground, and to the left of the figure 4 is a plow 8. Two objects 9 and 10 are also located between and in rear of both figures, the object 9 being larger than the object 10. The figure 4 is shown in shirt-sleeves and general working apparel, and the figure 5 is illustrated in full attire.

Having thus described the invention, what is claimed as new is—

The design for a badge, herein shown and described.

In testimony that I claim the foregoing as my own I have hereto affixed my signature in the presence of two witnesses.

CHARLES M. DAYTON.
